UNITED STATES PATENT OFFICE.

AUGUST O. JOHNSON, OF CHICAGO, ILLINOIS.

WINDOW-SASH.

1,103,774.

Specification of Letters Patent. Patented July 14, 1914.

Application filed November 20, 1913. Serial No. 802,095.

To all whom it may concern:

Be it known that I, AUGUST O. JOHNSON, a subject of the King of Norway, residing at Chicago, in the county of Cook and State 5 of Illinois, have invented certain new and useful Improvements in Window-Sashes; and I do declare the following to be a full, clear, and exact description of the invention, such as will enable others skilled in the art 10 to which it appertains to make and use the same.

This invention relates to improvements in window sashes and more particularly to those being provided with means for readily 15 detaching the panes of glass therefrom.

The primary object of the invention is to provide a sash of this character so constructed as to obviate the necessity of using putty to secure the window panes in place.

20 A secondary object is to provide a sash of this character which will be simple, strong and neat in appearance, and which will effectually exclude the most severe weather.

With these objects in view, the invention 25 resides in certain novel features of construction and combination herein described and claimed, and shown in the drawings wherein—

Figure 1 is an inner side view of a sash 30 constructed in accordance with my invention. Fig. 2 is an outer side view thereof. Figs. 3 and 4 are horizontal sectional views on the lines 3—3 and 4—4 of Fig. 1. Fig. 35 5 is a detail side elevation of a portion of the sash showing the manner in which the pane carrying frames are secured in the frame of the sash; and Fig. 6 is a detail of one of the pane securing bars.

In the drawings I have shown my improved window sash as comprising a frame 40 1 of suitable construction, a removable window pane 2, and a pane retaining frame 3 removable with said pane.

Secured within the opening of the frame 45 1 in any suitable manner, such as by screws 4, is a metal strip 5 which extends on all four sides of said opening and has its outer edge bent inwardly to form a channel 6. This channel is partially filled with a packing 50 7, of felt or other suitable material, for a purpose to appear.

The pane retaining frame 3 is shown as constructed of angle iron bars 8 within the angle of which the pane 2 is adapted to seat.

55 A second frame 9 comprising angle bars

9' overlies the pane 2 and seats within the outwardly projecting flange of the bars 8 and fastening screws 10 are then passed through the outwardly projecting flanges of the frames 3 and 9 and threaded into 60 reinforcing strips 11. The above-mentioned flanges of the frame 9 are preferably notched as at 12 for the reception of the screws 10 whereby the bars 9 may be moved closer to or farther from the frame 3 for the accommodation of panes of different thickness.

In order to removably secure the outwardly projecting flanges of the frames 3 and 9 and the strip 11 within the channel 6 and in contact with the packing 7 therein, 70 I form the strip 5 with oppositely disposed slots 13 in which cam noses 14 of pivoted latches 15 carried by the frame 3 are adapted to project. I also provide the frame 3 with knobs 16 at its upper and lower ends for 75 facilitating the removal of said frame and its coacting parts.

Although I have described my invention with considerable minuteness I do not wish to be limited to details other than those 80 pointed out in the appended claim, and it will be obvious that although I have shown my invention constructed for application to an ordinary window frame, it may be inserted within a sash of common construction 85 by making necessary alterations.

What is claimed as new is:

A window sash comprising: a frame, an inwardly extending channeled flange secured within the opening thereof, packing in the 90 channel of said flange, an angle iron frame, a window pane seated within the angle thereof, a second angle iron frame resting within said first mentioned angle iron frame and in contact with said pane, a reinforcing 95 strip seated within the angle of said second mentioned angle iron frame, screws passing through said angle iron frames and into said reinforcing strip, and means for retaining the outwardly projecting flanges of 100 said angle iron frames and said reinforcing strip seated within said channel and in contact with said packing.

In testimony whereof I have hereunto set my hand in presence of two subscribing witnesses.

AUGUST O. JOHNSON.
